ELECTRIC LANTERN

Harold J. Anderson, Kansas City, Mo.

Application May 26, 1958, Serial No. 51,091

Term of patent 14 years

(Cl. D48—24)

Fig. 1 is a top plan view of an electric lantern, showing my new design;

Fig. 2 is a front elevational view thereof; and
Fig. 3 is a side elevational view thereof.

The sides of the battery member and switch not shown are substantially the same in appearance as the sides shown.

I claim:

The ornamental design for an electric lantern, as shown and described.
